UNITED STATES PATENT OFFICE.

WARREN C. GLEASON, OF CHICAGO, ILLINOIS.

DESIGN FOR A BUSINESS CARD OR ENVELOPE.

SPECIFICATION forming part of Design No. 19,433, dated November 19, 1889.

Application filed September 28, 1889. Serial No. 325,451. Term of patent 3½ years.

To all whom it may concern:

Be it known that I, WARREN C. GLEASON, a citizen of the United States, residing at Chicago, county of Cook, and State of Illinois, 5 have invented and produced a new and original Design for a Business Card or Envelope, which is set forth in the following specification, reference being had to the accompanying drawing, forming a part thereof.

10 This design is for the face or back of a business card or envelope; and it consists of a field or background having upon it a conventional representation of a many-storied building presenting to the view a dead-wall, and

15 upon the top of such building a conventional representation of a telephone and the figure of a man using the same, the conventional representation of the circuit-wire pertaining to such telephone extending away from the

20 building and encircling a conventional representation of the globe of the earth, the line which conventionally represents the circuit-wire extending thence away from the said conventional representation of the globe and 25 merging in the initial of a phrase.

I claim—

The design for a business card or envelope herein described and illustrated, comprising the conventional representation upon a field or background of a many-storied building 30 presenting to view a dead-wall, and upon the top of such building the conventional representation of a telephone and a person upon the same, and the conventional representation of the circuit-wire from such telephone 35 encircling a conventional representation of the globe of the earth, and thence merging in the initial of a phrase, substantially as set forth.

In testimony whereof I have hereunto set 40 my hand, in the presence of two witnesses, at Chicago, Illinois, this 24th day of September, 1889.

WARREN C. GLEASON.
